UNITED STATES PATENT OFFICE

107,847

DESIGN FOR A COFFEE BREWER

Charles Abrams, Chicago, Ill., assignor to Universal Coffee Co., Chicago, Ill., a corporation of Illinois

Application November 12, 1937, Serial No. 72,817

Term of patent 7 years

To all whom it may concern:

Be it known that I, Charles Abrams, a citizen of the United States, residing at Chicago, in the county of Cook and State of Illinois, have invented a new, original, and ornamental Design for a Coffee Brewer, of which the following is a specification, reference being had to the accompanying drawing, forming a part thereof.

In the drawing:

The figure is a perspective view of the coffee brewer, showing my design.

I claim:

The ornamental design for a coffee brewer, substantially as shown.

CHARLES ABRAMS.
